ATTORNEY.

UNITED STATES PATENT OFFICE.

ADELAIDE W. WHITE, OF SYRACUSE, NEW YORK.

BELT-BUCKLE.

1,319,547.

Specification of Letters Patent.

Patented Oct. 21, 1919.

Application filed May 14, 1918. Serial No. 234,377.

To all whom it may concern:

Be it known that I, ADELAIDE W. WHITE, a citizen of the United States of America, and resident of Syracuse, in the county of 5 Onondaga, in the State of New York, have invented new and useful Improvements in Belt-Buckles, of which the following, taken in connection with the accompanying drawings, is a full, clear, and exact description.

10 This invention relates to certain improvements in belt buckles, the object being to produce a light, strong and durable buckle in which the ends of the belt may be easily and quickly adjusted to various girths with- 15 out liability of accidental loosening.

Another object is to construct the buckle so as to lie flatwise as nearly as possible within the combined thicknesses of the overlapping portions of the belt and also to dis- 20 play as little as possible of the buckle in symmetrical rectangular form.

Other objects and uses relating to specific parts of the buckle will be brought out in the following description.

25 In the drawings—

Figure 1 is a perspective view of a belt with my improved buckle in operative position.

Fig. 2 is an enlarged longitudinal sec- 30 tional view taken on line 2—2, Fig. 1.

Fig. 3 is an enlarged transverse sectional view taken on line 3—3, Fig. 1.

Figs. 4 and 5 are perspective views of the base plate and slide plate constituting the 35 two elements of the buckle.

Figs. 6 and 7 are longitudinal sectional views, similar to Fig. 2, of the same buckle showing different methods of threading the belt therethrough.

40 As illustrated, this buckle comprises a base plate —1— and a slide plate —2—, each plate being provided near its ends with transverse slots —3— and —3'—, the plate —1— having its opposite longitudinal edges provided with lengthwise flanges —4— overhanging the adjacent portions of the main body to form lengthwise grooves —5— which are open at one end, but are closed at their opposite ends by abutments 45 —6— forming integral parts of the flanges and plate.

The main body of the plate —1— is flat and approximately rectangular so that the flanges or ribs —4— are practically parallel, 55 the ends of the main body being extended relatively short distances beyond the cor-

responding ends of said flanges which in turn extend beyond the slots —3— in the opposite ends of the main body, to more effectively hold the ends of the plate —2— 60 against springing away from the plate —1— when the buckle is adjusted on the belt ready for use.

The slide plate —2— is of approximately the same width as the main body of the 65 base plate —1—, but is somewhat shorter than said base plate so that when mounted thereon in sliding interlocking engagement with the flanges —4—, its slots —3'— will be out of registration with or mainly be- 70 yond the inner edges of the slots —3— so that the portions of the belt passing through said slots of either plate will not interfere with those portions which pass through the slots of the other plate, thus permitting the 75 main bodies of both plates to lie close together, except for the single thickness of belt between them, as shown in Fig. 2, in which the plates are substantially parallel.

As shown in Figs. 1, 2 and 3, the opposite 80 ends of the belt, as —A—, are passed across the inner faces of the opposite ends of their respective buckle sections or plates —1— and —2—, and thence outwardly through the slots therein and along the outer faces 85 of the main portions of the bodies between said slots so that when the plates are assembled by sliding interlocking engage- 90 ment of the plate —2— with the flanges —4— of the plate —1—, the portion of the belt between the slots —3'— will be im- 95 pinged between the adjacent faces of both plates, while the portions of the belt at the outer sides of the slots —3— will be im- pinged between the opposite ends of both plates.

The end of the belt passing through the slots —3— extends beyond the abutment —6—, while the other end of the belt ex- 100 tends in the opposite direction beyond the adjacent end of the plate —2— so that any tendency to expand the belt when adjusted for use is resisted by the abutments —6— 105 engaging the adjacent end of the slide plate —2—, and yet the buckle sections may be readily detached one from the other by sim- 110 plly drawing both ends of the belt in op- posite directions until the plate —2— is withdrawn from the flanges —4—.

When the buckle sections are thus sepa- 110 rated, the ends of the belt may be readily drawn through the slots of their respective

plates for readjustment to conform to any different girth.

When the belt is properly readjusted in one or both of the sections —1— and —2—, the latter may be reassembled in the manner previously described, and when so assembled the portion of the belt between the slots —3'— lies wholly between the slots —3— and portions of the belt extending therethrough which serve in a measure to retain the ends of the belt and buckle sections against accidental displacement.

In Fig. 6, one end of the belt is shown as extended across the outer faces of opposite ends of the section —2— and then along the inner face of said plate or section between the slots —3'—.

In Fig. 7, the plates of the buckle are merely reversed from that shown in Figs. 1 and 2.

The manner of assembling the ends of the belt upon their respective buckle plates and of slidably interlocking said plates one with the other, as hereinbefore described, is found to be effective for all ordinary purposes, but if for any reason either end of the belt should tend to slip relatively to its cor-

responding buckle section, this may be obviated by providing said section with one or more teeth or spurs —7— struck up therefrom so as to embed itself in the belt under strain, as shown more clearly in Figs. 2 and 5.

What I claim is:

A belt buckle composed of two substantially flat sheet metal plates detachably slideable lengthwise one upon the other and provided with coöperative means for holding them against lateral displacement, each plate having a pair of slots, one near each end, the portion of each plate between its slots being of considerably greater area than that of either slot, in combination with a belt having one end slideable through the slots of one plate, the other end of said belt being slideable through both slots of the other plate and across the intervening portion thereof.

In witness whereof I have hereunto set my hand this 6th day of May, 1918.

ADELAIDE W. WHITE.

Witnesses:

H. E. CHASE,
ALICE M. CANNON.
